FIG. 2.

FIG. 5.

FIG. 4.

FIG. 3.

FIG. 1 is a perspective view of a multiple-purpose hand tool, showing the same in an open condition;

FIG. 2 is a plan view showing the tool in closed condition, and illustrating the side not shown in FIG. 1;

FIGS. 3 and 4 are end views of opposite ends of the tool; and

FIG. 5 is a side elevation.

The side not shown in FIG. 5 is, except at the distal ends of the handle elements, the mirror image of the side shown therein.

I claim:

The ornamental design for a multiple-purpose hand tool, substantially as shown and described.
